UNITED STATES PATENT OFFICE.

EDWARD P. SHELDON, OF BROOKLYN, NEW YORK, ASSIGNEE TO R. HOE AND CO., OF NEW YORK, N. Y., A CORPORATION OF NEW YORK.

SHEET DELIVERY.

Application filed March 26, 1921. Serial No. 455,906.

To all whom it may concern:

- Be it known I, EDWARD P. SHELDON, a citizen of the United States, residing at Brooklyn, county of Kings, and State of New York, have invented certain new and useful Improvements in Sheet Deliveries, fully described and represented in the following specification and the accompanying drawings, forming a part of the same.
- 10 This invention relates to certain improvements in sheet delivery mechanism and it has been designed particularly for a pile delivery in which the sheets are deposited superposed in piles.
- 15 In pile deliveries or in piling delivered sheets as they come from the press it is desirable that the sheets be deposited in different piles so that time will be given for the printed surface of a deposited sheet to dry before another sheet is deposited thereon so as to prevent smutting of the sheets.
- 20 Various constructions have been proposed for alternately piling sheets in different piles to permit of the sheets having sufficient time to dry. For instance it has been proposed to provide a sheet transferring mechanism which takes the sheets as they are forwarded from the press and drops them alternately in two piles, the piles being 25 arranged at one side of the sheet forwarding means. This, while it gave the sheets a certain time to dry, did not give a sufficient time where the delivery was used with high speed machines. It was then proposed 30 to duplicate the transferring mechanism upon the other side of the sheet forwarding means and transfer sheets to the four piles alternately, first to one side and then to the other of the sheet forwarding means.
- 35 This transferring, while it gave more time for the sheets to dry required an arrangement of the delivery which was awkward under some circumstances, in that the sheet transferring mechanism extended outwardly 40 on both sides of the delivery and required a wide space in which to operate which was frequently disadvantageous, particularly in press rooms of small floor capacity. This arrangement, furthermore, required a duplication of the parts which made it somewhat expensive to install, and furthermore 45 the sheets transferred by it at one side were 50 deposited in the piles printed side down which was disadvantageous unless a complicated sheet reversing mechanism were used to reverse the sheet.
- 55 It is the especial object of the present invention to provide a construction in which there is provided a sheet transferring mechanism which will take the sheets from the forwarding mechanism and which is arranged at one side thereof and operates to alternately deposit the sheets in three or more piles so as to give the sheets a sufficient time to dry, and to permit all the 60 sheets to be deposited in the piles with the printed side up without necessitating the use of a sheet reversing mechanism.
- 65 A further object of the invention is to provide a construction in which but one sheet transferring mechanism is employed for transferring and depositing sheets in three or more piles thus producing a simple economical construction to build, and one 70 which being arranged on one side of the forwarding devices can be attended to by one sheet tender.
- 75 With these and other objects not specifically referred to, the invention consists in certain novel combinations and parts which will be fully described in connection with the accompanying drawings which show a preferred embodiment of the invention, and the novel features of which will be then 80 pointed out in the claims, hereunto subjoined.
- 85 Referring now to these drawings
- Figures 1 to 4 inclusive, are diagrammatic side elevations of the delivery end of the machine showing the improved delivery as employed in alternately piling sheets 90 in four piles.
- Figure 5 is a side elevation, partly in section and partly broken away of part of the delivery shown in Figs. 1 to 4, the parts 95 being shown in detail.
- Figure 6 is an end view of the construction shown in Fig. 5, the view being taken in the direction of the arrow *a* of that figure, showing the cams and operating parts 100 for operating the sheet transferring mechanism, the view being partly in section.
- Referring now to these drawings, the invention has been illustrated in connection

with a machine in which a web is forwarded and from which the sheets to be piled are cut, though it will be understood that the invention is intended for and may be used in other relations. As shown, there is a web W which may come from a printing mechanism not illustrated. This web W is forwarded by forwarding means, shown as a pair of rolls 1, 2 mounted in the frames 10 3 of the machine. In the construction illustrated, this web is severed into sheets by a suitable cutting mechanism, the severance preferably taking place after the web has been seized by certain sheet taking devices 15 hereinafter referred to. For effecting this severance there is provided a pair of cutting cylinders 4, 5 provided with the usual cutting knives 6, 7.

Arranged at one side of the sheet forwarding rolls is provided a sheet transferring mechanism by which the sheets are transferred sidewise of the forwarding mechanism and in one direction, and deposited at three or more points, the sheets 20 25 in the particular delivery illustrated being piled, and in machines constructed in the best forms, one transferring mechanism is employed for transferring the sheets and for alternately depositing them at the 30 points of final delivery.

As shown, this transferring mechanism comprises a travelling carrier in the form of a pair of chains 8, 9, these chains being arranged on opposite sides of the machine and passing over sprockets 10, 11, mounted on shafts 12, 13 arranged at opposite ends of the delivery and extending across the machine, one of these shafts, as 12, being a driven shaft driven through suitable connections, hereinafter referred to. This carrier is provided with suitable sheet taking devices shown in the form of grippers 14, these grippers being oppositely arranged on the carrier chains so as to grip the sheet at each 10 15 edge and forward it evenly.

In the best constructions and in the machine shown, the sheets will be cut from the web while the web is being held by the grippers. To effect this the forward sprockets 10 and the shaft therefor, are arranged in advance of the cutting cylinders 4, 5, before referred to, between them and the forwarding rolls, and the cutting cylinders are recessed at their ends, as indicated at 15, to permit the grippers to pass them while holding on to the sheet. The sheet taking grippers, where grippers are employed for taking the sheets, are provided on the carrier in pairs and in sufficient numbers to handle the 50 55 sheets which are to be delivered.

The specific construction of the grippers may be somewhat varied, but as illustrated they include a fixed jaw 16 (see Fig. 5) and a movable jaw 17 pivoted to a stud 18 on an 65 arm 19 secured to a block 20 fast to the side

of the carrier chain. These grippers are normally held in closed or sheet gripping position by springs 21, the pivoted jaw of the grippers being opened against this spring to take and release a sheet. To effect the 70 seizure of the sheet before it passes the cutting mechanism, the shaft 12 on which the forward sprockets 10 are carried, is provided with a cam 22 which contacts with a roll 23 co-operating with the movable jaw of the 75 gripper 17, before referred to, and by depressing it the jaws are opened to take the sheet. With this construction the sheet is positively held while it is being cut from the web and while it is being transferred to 80 its point of delivery.

In the particular construction illustrated the sheets are deposited in piles, and four such piles are shown marked 24, 25, 26, and 27, and the carrier is provided with sets of 85 grippers for taking sheets for delivery to each pile. Further, in the particular machine illustrated, the sheets are delivered successively to the different piles, that is, sheets a are delivered to pile 24, sheets b to pile 25, 90 sheets c to pile 26, and sheets d to pile 27. To effect this, operating means are provided for opening the grippers at the proper points to deliver each fourth sheet to the same pile. While these means may be varied somewhat 95 in construction, as shown these gripper operating means are normally in such position as to permit the grippers to pass them, each means operating at every fourth sheet to cause the grippers to drop such sheet on the 100 pile which it controls. As shown where the sheets are to be piled in four piles there are provided three of these movable gripper controlling mechanisms and one stationary one, as for the last pile a movable mechanism is 105 not necessary. These movable mechanisms are indicated generally in Figs. 1 to 4 by the numerals 28, 29 and 30, and the stationary controlling mechanism is indicated at 31. The movable mechanisms and the means for 110 operating them are the same, and it is necessary to describe but one in detail. It may be stated here, however, that each movable mechanism is controlled by an individual cam, these cams being indicated in Fig. 6 115 by the numerals 32, 33 and 34, these controlling cams being carried on a shaft 35 extending across the machine and taking bearing in brackets 36 on the frames 3, before referred to.

Referring now to Fig. 5, which shows one movable gripper controlling mechanism in detail, there is provided a cam shoe 37 carried on an arm 38 fast on a rock shaft 39 extending across the machine, one of these 125 shoes being provided at each side of the machine to operate both grippers of a pair. This rock shaft finds bearing in the frames 3 of the machine, before referred to, and has fast thereon an arm 40 to which is connected 130

at 41 an operating rod 42, at one side of the machine. This rod 42 at its other end is fast to an arm 43 on a short rock shaft 44 mounted in the frame 3, before referred to, 5 this rock shaft also having secured thereto a second arm 45 connected at its end with a rod 46 which terminates in a yoke 47 passing about the shaft 35, before referred to. This yoke carries a cam roll 48 which runs on one 10 of the operating cams, as the cam 32.

Fast on the shaft 39 is a second arm 49 to the end of which is secured a spring rod construction, indicated at 50. The cam 32 is so formed that the high part of the cam 15 through the rods 46 and 42 holds the shaft 39 rocked against the spring to hold the cam shoe 37 out of the path of the roll 23 on the grippers, so that the grippers normally pass under the shoe without being operated there- 20 by. When the time has come for a sheet, as sheet *d*, to be deposited on pile 27, the low part of the cam 32 permits the shaft 39 to be rocked by the spring rod 50 and the shoe drops so as to be in the path of the grippers 25 thereby causing the rolls 23 to actuate the movable jaws 17 of the grippers and cause the grippers to release the sheet so as to drop the sheet on the pile.

Similarly each of the gripper controlling 30 mechanisms 29 and 28 are operated from the cams 33 and 34, respectively through rods 51 and 52 and connections similar to those already described.

The fixed gripper controller 31 is also 35 in the form of a cam shoe and operates each pair of grippers as they come along, but as only one pair of grippers at this point have a sheet, that is, sheet *a*, it is unnecessary to move this sheet out of the 40 way to permit the grippers to pass under it without operating.

The sequence of operations is clearly 45 shown in Figs. 1 to 4. In Fig. 1 a sheet is shown as being deposited on pile *d*, the gripper controlling mechanism 30 being shown in its operative position to open the grippers, and the gripper controlling mechanisms 29 and 28 being shown as raised to permit sheets *a*, *b* and *c* to pass. In Fig. 50 2, sheet *c* is shown as being deposited, the mechanism 29 being lowered to its operative position, but the mechanism 28 being shown as raised to permit the sheet *a* to pass and sheet *b* to come into position and new sheets 55 *a*, *b* being shown as coming in at the left hand end of the figure and the controlling mechanism 30 being shown as raised. In Fig. 3 the controlling mechanism 28 has been made operative to deposit sheet *b* sheet 60 *a* being passed and new sheets *a*, *b* shown at the left hand end of the figure having advanced further along, the controlling mechanism 30, and the mechanism 29 being shown as out of the way. In Fig. 4, sheet *a* at 65 the right hand end of the figure has been

deposited and new sheets *a*, *b* and *c* are shown as being transferred, the controlling mechanisms 30, 29, and 28 all being shown as in raised position to permit the passage of the sheets.

With the construction as described, the sheets are delivered at three or more points and all with the same side up, and a sufficient length of time is provided for the sheets to dry. Furthermore, all the mechanisms are arranged at one side of the sheet 70 forwarding rolls so that an economical arrangement of space is provided for and a simple mechanism for effecting the depositing of the sheets provided. It will, of course, be understood that the sheets may be delivered to the piles in orders other than successive, it being simply a question of the timing of the cams for operating the gripper controlling mechanisms.

Where the sheets are deposited in piles, as in the preferred embodiment of the invention illustrated, means will preferably be provided for supporting the piles and for lowering the pile supports by a step by step 80 movement, as the piles increase, and in the best constructions means will be provided for evening up the sheets as the piles increase in size, and each pile of sheets is supported. The pile supports are operated in 85 a similar manner and a description of one will suffice for all. As shown, referring to Fig. 5, the sheets are piled on to tables 54 supported in parallel carrier chains 55, 56, which pass around sprockets 57 and 58. 90 One pair of these sprockets, as sprockets 58 are driven through gears 59 from gears 60 on a shaft 61 extending around the machine and common to all the piles. This shaft 61 is provided at one end with a driving gear 100 62 meshing with a gear 63 on a short shaft 64. This short shaft has fast thereon a ratchet 65 which is given a step by step movement through a pawl 66 operated from a rod 67 through a roll 68 (see Fig. 6) and a 110 cam 69 on the other end of the shaft 35, before referred to. With this construction the pile tables are given a step by step downward movement as the pile increases in size.

Operated also from the cam shaft 35, before referred to, is the mechanism preferably employed for evening up the sheets as they are deposited on the piles. As illustrated this evening mechanism includes a vibrating 115 striker which strikes against the edges of the sheets and forces them against an abutment. One of these strikers and the abutment is provided for each pile and are all operated simultaneously. As shown the 120 striker consists of a plate or plates 70 carried on an arm 71 (see Fig. 5) on a rock shaft 72 mounted in the frames 3 of the machine, before referred to, this shaft being rocked against a spring rod construction 125 70

73. The shaft is rocked by means of an arm 74 to which is connected one end of a short rod 75 having at one end a yoke 76 engaging the shaft 35, before referred to, 5 and carrying a cam roll (see Fig. 6) 77 which engages a shaking cam 78 on the cam shaft 35. The arm 74 is also connected through a rod 79 to an arm 80 similar to the arm 74, before referred to, on a shaft 10 81 on which is an arm 82 carrying a shaker plate 83 similar to the plate 70, before referred to. This arm 80 is also connected to one end of a rod 84 which operates the next adjacent shaker plate. These plates 15 shake the sheets against abutments or stops in the form of plates 85 carried on bars 86 supported in any suitable manner, as on studs 87 in the machine frame. With this construction the sheets as they are piled on 20 the piling tables are evened up edgewise.

The various mechanisms referred to may be driven in any suitable manner. As illustrated there is a large driving gear 88 suitably mounted on a shaft 89 in the frames 3 25 of the machine, this gear being driven from a gear 90 operated from any suitable source of power not illustrated. The forwarding roll 1 is driven from the gear 90 through an intermediate gear 91 and a gear 92 on 30 the shaft 93 of the forwarding roll. This gear 92 also drives the sprockets 10 through an intermediate gear 94 and a gear 95 (see Fig. 6) on the sprocket shaft 12. The cam shaft 35 is driven from the gear 88 through 35 a gear 96 carried by a shaft 97 journaled in the side frames 3, this gear meshing with a gear 98 on the shaft 35. The shaft 97 also carries a gear 99 which meshes with a gear 100 on the shaft 101 of the cutting cylinder 5, and by which the lower cutting cylinder is driven. This cutting cylinder shaft also carries a gear 102 which meshes with a gear 103 on the shaft 104 of the upper cutting cylinder 4, whereby the upper cylinder 45 is driven.

With the construction described, a very efficient delivery has been provided for the purposes specified, and while a preferred embodiment of the invention has been shown and described, it will be understood that various changes may be made in the specific construction and arrangements of the parts without departing from the invention as defined in the claims annexed hereto.

55. What I claim is:

1. In a delivery, the combination of forwarding means, and means for transferring sheets from the forwarding means and depositing the sheets at three or more points in the line of travel of the sheets and at one side of the sheet forwarding means.

2. In a delivery, the combination of forwarding means, means for cutting sheets from a web, and means for transferring the 65 cut sheets from the cutting mechanism and

depositing the sheets at three or more points in the line of travel of the sheets and at one side of the sheet forwarding means.

3. In a delivery, the combination of forwarding means, three or more pile supports 70 arranged in line at one side of the forwarding means, and means for transferring sheets from the forwarding means and depositing them on the pile supports.

4. In a delivery, the combination of forwarding means, means for cutting sheets from a web, three or more pile supports arranged in line at one side of the forwarding means, and means for transferring the cut sheets from the cutting mechanism and 80 depositing them on the pile supports.

5. In a delivery, the combination of forwarding means, three or more pile supports arranged in line at one side of the forwarding means, and means for transferring 85 sheets from the forwarding means and depositing them successively on the pile supports.

6. In a delivery, the combination of forwarding means, means for cutting sheets 90 from a web, three or more pile supports arranged in line at one side of the forwarding means, and means for transferring the cut sheets from the cutting mechanism and 95 depositing them successively on the pile supports.

7. In a delivery, the combination of web forwarding means, means for cutting sheets from the web, a sheet transferring mechanism provided with sheet taking devices, 100 means for actuating the devices to take the web before it is cut and to hold the sheet after the cut, three or more pile supports arranged at one side of the forwarding means, and means whereby the sheet taking devices are caused to deposit the sheets successively on the pile supports.

8. In a delivery, the combination of web forwarding means, means for cutting sheets from the web, a sheet transferring mechanism provided with sheet taking devices, means for actuating the devices to take the web before it is cut and to hold the sheet after the cut, and means whereby the sheet taking devices are caused to deposit the 115 sheets at three or more points in the line of travel of the sheets and at one side of the sheet forwarding means.

9. In a delivery, the combination of forwarding means, three or more pile supports 120 arranged in line at one side thereof, a travelling carrier, sheet taking devices thereon, and devices for actuating the sheet taking devices to deposit successive sheets successively on the piles.

10. In a delivery, the combination of forwarding means, three or more pile supports arranged at one side thereof, a carrier travelling over the piles, sheet taking grippers on the carrier normally held in sheet hold- 125

ing position, and devices, one for each pile for actuating the grippers to release successive sheets over different piles.

11. In a delivery, the combination of forwarding means, three or more pile supports arranged in line at one side thereof, a carrier travelling over the piles, sheet taking grippers on the carrier, normally held in sheet holding position, and a fixed device for the last pile, and movable devices for the other piles for actuating the grippers to release successive sheets over different piles.

12. In a delivery, the combination of forwarding means, three or more pile supports arranged in line at one side thereof, a carrier travelling over the piles, sheet taking grippers on the carrier normally held in sheet holding position, movable operating devices for actuating the grippers to release a sheet, a controller shaft, and cams thereon one for each device for controlling the movement thereof.

13. In a delivery, the combination of forwarding means, three or more pile supports arranged in line at one side thereof, a carrier moving over the piles and provided with sheet taking devices, and means for

causing the carrier to drop successive sheets on different piles.

14. In a delivery, the combination of forwarding means, three or more pile supports arranged in line at one side thereof, a carrier moving over the piles and provided with sheet taking devices, means for actuating the sheet taking devices to drop successive sheets on different piles, a pile evening mechanism, a shaft, and cams on the shaft for actuating the evening mechanism and the actuating means for the sheet taking devices.

15. In a delivery, the combination of forwarding means, three or more pile supports arranged in line at one side thereof, a carrier moving over the piles, grippers on the carrier normally closed, a fixed cam at the last pile for opening the grippers to drop a sheet thereon, spring controller cams for the other piles normally held out of the way of the grippers, a shaft, and operating cams thereon controlling the spring cams.

In testimony whereof, I have hereunto set my hand.

EDWARD P. SHELDON.
